(57) **CLAIM**

The ornamental design for foldable glasses, as shown and described.

DESCRIPTION

FIG. 1 is an isometric view showing our new design in the open configuration;

FIG. 2 is a front view showing our new design in the open configuration;

FIG. 3 is a right side elevational view showing our new design in the open configuration;

FIG. 4 is a rear view showing our new design in the open configuration;

FIG. 5 is a left side elevational view showing our new design in the open configuration;

FIG. 6 is a top view showing our new design in the open configuration;

FIG. 7 is a bottom view showing our new design in the open configuration;

FIG. 8 is an isometric view showing our new design in the folded configuration;

FIG. 9 is a front view showing our new design in the folded configuration;

FIG. 10 is a right view showing our new design in the folded configuration;

FIG. 11 is a rear view showing our new design in the folded configuration;

FIG. 12 is a left side view showing our new design in the folded configuration;

FIG. 13 is a top view showing our new design in the folded configuration; and,

FIG. 14 is a bottom view showing our new design in the folded configuration.

Any broken lines shown in the drawings are for illustrative purposes only and form no part of the claimed design.
